UNITED STATES PATENT OFFICE.

PHENES MISH, OF SAN FRANCISCO, CALIFORNIA.

CIGAR-TIP PROTECTOR.

SPECIFICATION forming part of Letters Patent No. 359,358, dated March 15, 1887.

Application filed November 27, 1886. Serial No. 220,098. (No model.)

To all whom it may concern:

Be it known that I, PHENES MISH, of the city and county of San Francisco, State of California, have invented an Improvement in 5 Cigar-Tip Protectors; and I hereby declare the following to be a full, clear, and exact description of the same.

My invention relates to a device for protecting the tips of cigars; and it consists in the 10 improved tip protector which I shall herein-after fully describe and claim.

Referring to the accompanying drawings for a more complete explanation of my invention, the figure is a view of a cigar having the 15 protector.

A is the body of a cigar, and B is the protector or tip, composed of a thin tissue of rubber, which is applied to the finished end, extending a short distance along the cigar and 20 having its extreme point made open, as shown, so that the tip of the cigar projects through it, and when the cigar is to be smoked this tip is cut off, so that there may be the proper draft through the cigar. The sides of the protector 25 are perforated with a number of small holes, C, through which the cigar is exposed, and by which it is allowed to be somewhat moistened when placed in the mouth without becoming so softened as to be crushed or made disagreeable for the smoker. At the same time the 30 flavor of the cigar is more readily observed, and the openings also assist in holding the cigar more firmly, because the teeth will take hold through the openings. If the draft of the cigar

is not satisfactory, perforations may be made 35 through its outer skin in line with one or more of the holes C, so as to improve the draft. By the use of these mouth-pieces the inconvenience of carrying the ordinary cigar-holder is obviated. At the same time the disagreeable 40 odor of nicotine communicated to the clothing of the smoker carrying such holder is done away with, and but a small percentage is added to the cost of the cigars.

I am aware that thin imperforated rubber 45 tips or shields applied permanently to the mouth ends of cigars are common, and I am also aware that rubber mouth-pieces for cigars provided with perforations in the walls of the cigar-receiving portions are not new, and I do 50 not claim such as my invention.

Having thus described my invention, what I claim as new, and desire to secure by Letters Patent, is—

An exterior envelope or tip made of a thin 55 tissue of rubber fitted permanently to the end of the cigar, so as to leave the point exposed, and having openings or perforations made through the envelope, by virtue of which the sides of the cigar are moistened when it is 60 placed in the mouth, substantially as herein described.

In witness whereof I have hereunto set my hand.

PHENES MISH.
